ADJUSTABLE LAST

Application filed September 28, 1929. Serial No. 395,870.

This invention relates to the art of shoe manufacture and deals more specifically with an adjustable last.

In the art of shoe manufacture it is required that a large number of lasts be kept on hand in order to meet the requirements of factory production. The cost of maintaining such a large number of lasts adds materially to overhead charges. Due to the fact that a pair of lasts of a certain size are necessary in order to manufacture a pair of shoes of a certain given size, it is necessary to keep on hand a large number of pairs of different sizes of lasts. It will be seen, therefore, that if there is provided a last which may be used for more than one size, the necessary cost of lasts will be considerably diminished.

Also, in the manufacture of turn shoes two pairs of lasts are now necessary in connection with the production of a single pair of shoes; one pair of lasts being used for the first lasting operation, and a second pair of lasts, slightly larger in size, being used in the re-lasting operation.

It is therefore an object of this invention to provide a last which is adjustable to two or more sizes.

Further, it is an object of this invention to provide an adjustable last which is relatively cheap to construct and easy to manipulate.

Finally, it is an object of this invention to produce an adjustable last which is provided with an efficient mechanical movement whereby the use of such adjustable last will not impede or hinder the usual operations in shoe manufacture.

The manner in which the present invention is carried out will be more readily understood from the following description taken in connection with the accompanying drawings in which:

Fig. 1 is a side elevation view of a device embodying the present invention;

Fig. 2 is a detailed sectional view of said device, the forward portion of the last being broken away; and

Fig. 3 is a detailed longitudinal sectional view of the actuating mechanism embodied in the present invention.

Referring in detail to the drawings, the last 10 is seen to comprise a forward or toe section 11 and a rearward or heel section 12. Dowel pins 13 (one only being shown in the drawings) are fixed to the rear section 12 and arranged for sliding engagement with the holes 14 formed in the forward section 11. The holes 14 are positioned with respect to the dowel pins 13 to insure proper alignment between the sections 11 and 12 of the last 10. A metallic band 15 is fixed to one of the sections of the last such as, for example, section 12, the band being shaped to conform accurately to the contour of the last at the portions thereof embraced by said band. The portion 15a of the band 15 embraces the section 12 and is fixed thereto. The portion 15b of the band 15 embraces the forward section 11 of the last in sliding engagement therewith in order to permit relative movement between the sections 11 and 12. The band 15 serves to maintain the sections 11 and 12 in proper alignment and in this respect it cooperates with the dowel pins 13 and 14. It will be understood, of course, that the width of the band 15 will depend for the most part upon the extent of adjustability required in the last, it merely being necessary that the band be sufficiently wide to bridge the space between the sections 11 and 12 when they are in their most widely spaced position corresponding to the largest size for which the last is adjusted. In actual practice it has been found that satisfactory results may be obtained by lasts adjustable to produce a size variation of $\frac{1}{8}$, $\frac{1}{4}$ or $\frac{3}{8}$ of a size.

Referring now in detail to Figs. 2 and 3, the mechanism for spacing the sections 11 and 12 will now be described in detail. This mechanism 20 comprises a bolt 21 having a head 22 which is designed to facilitate the turning of bolt 21. A shoulder 23 is provided in the bolt 21 and the shank portion 24 of the bolt is threaded substantially throughout its length as at 25. Loosely mounted upon the shank 24 of the bolt 21 is a circular collar 26 which abuts against the shoulder 23. A wedge or cam face 27 shaped generally as shown in Fig. 2 is fixed to diametrically opposite sides 100

of the collar 26. A second collar 30 internally threaded at 31 is mounted at the lower end of the shank 24 of the bolt 21 in threaded engagement therewith. The collar 30 is provided with wedge or cam faces 32 mounted on diametrically opposite sides of the collar 30 similar to the corresponding structures formed on the collar 26. Loosely mounted on the shank 24 of the bolt 21 is a coil spring 33.

Embracing the shank of the bolt 21 and the collars 26 and 30 is a cylindrical member 40 split longitudinally thereof into sections 41 and 42. The split springs 43 encircle the cylindrical section 41 and 42 and hold the same in associated relationship as shown in Figs. 2 and 3. The contiguous faces of the sections 41 and 42 are recessed at 44 as shown in Fig. 2 to embrace the wedge members 27 and 32 whereby to permit said members to come between the sections when they are in closest relationship with respect to each other. An oval-shaped collar 50 provided with screw 51 serves to hold the entire actuating mechanism in fixed relationship to one of the sections of the last 10.

The operation of the device is as follows: With the adjacent edges of the last sections 11 and 12 in abutting relationship, the last is 20 adjusted to its smallest size. Under these conditions the wedge members 27 and 32 are disposed within the recesses 44 formed in the cylindrical member 40. Now, if it is desired to increase the size of the last, the bolt is rotated through the head 22 thus causing the collar 30 to approach the collar 26. During this operation the wedge members 27 and 32 are made to approach each other thus causing them to enter between the sections 41 and 42 30 whereby to spread the same against the tension of the springs 43. The spreading of the sections 41 and 42 serves to separate the sections 11 and 12 with which they are in abutting contact by an amount equal to the distance by which sections 41 and 42 are separated. When it is desired to return the last 40 to its smallest size it is merely necessary to rotate the head 22 of the bolt 21 in the reverse direction, thus causing the wedge members 27 and 32 to return to the recessed portions 44 whereupon by tapping the sections 11 and 12 together the last assumes its original size.

Many changes in the present disclosure 55 will readily suggest themselves to those skilled in the art without departing from the spirit of this invention. It is therefore to be understood that the scope of this invention is not limited by the details of structure 60 herein disclosed, except as outlined in the appended claims.

Having thus described our invention, we claim:

1. An adjustable last comprising a forward section, a rearward section, means in-

ternally of said sections to maintain the same in alignment, means to vary the position of said sections relatively to each other, and a band secured to and surrounding one of said sections and embracing the other section to hold said sections together while permitting adjustment thereof.

2. An adjustable last comprising a forward section, a rearward section, means internally of said sections to maintain the same in alignment, means fixed to and surrounding one of said sections and embracing the other of said sections in sliding engagement therewith to hold said sections together and to maintain said sections in alignment, and means to vary the position of said sections relatively to each other.

3. An adjustable last comprising a forward section, a rearward section, means internally of said sections to maintain the same in alignment, means fixed to one of said sections and embracing the other of said sections and in sliding engagement therewith to hold said sections together and to maintain said sections in alignment, said last mentioned means surrounding and conforming substantially to the outer contour of the last at the portions thereof embraced thereby, and means to vary the position of said sections relatively to each other.

4. An adjustable last comprising a first section, a second section movable relatively thereto, a split cylinder mounted between said sections, one portion of said cylinder being adapted to contact with one of said sections and another portion of said cylinder being adapted to contact with the other of said sections, and means to vary the said portions relatively to each other, whereby to adjust the size of the last, and means holding said sections together and permitting adjustment thereof.

5. An adjustable last comprising a first section, a second section movable relatively thereto, a split cylinder mounted between said sections, one portion of said cylinder being adapted to contact with one of said sections and another portion of said cylinder being adapted to contact with the other of said sections, a wedge member, means to adjust the position of said wedge between said portions, whereby to adjust the size of the last and means holding said sections together and permitting adjustment thereof.

6. An adjustable last comprising a first section, a second section movable relatively thereto, a split cylinder mounted between said sections, one portion of said cylinder being adapted to contact with one of said sections and another portion of said cylinder being adapted to contact with the other of said sections, two wedge members, means to adjust the position of said wedges between said portions, whereby to adjust the size of the last.

and means holding said sections together and permitting adjustment thereof.

7. An adjustable last comprising a first section, a second section movable relatively thereto, a split cylinder mounted between said sections, one portion of said cylinder being adapted to contact with one of said sections and another portion of said cylinder being adapted to contact with the other of said sections, two wedge members, said portions of said cylinder being recessed to receive said wedge members therebetween, means to adjust the position of said wedges between said portions, whereby to adjust the size of the last, and means holding said sections together and permitting adjustment thereof.

8. An adjustable last comprising a first section, a second section movable relatively thereto, a split cylinder mounted between said sections, one portion of said cylinder being adapted to contact with one of said sections and another portion of said cylinder being adapted to contact with the other of said sections, two wedge members, means to adjust the position of said wedges between said portions, whereby to adjust the size of the last, spring means mounted between said wedge members, and means holding said sections together and permitting adjustment thereof.

9. An adjustable last comprising a first section, a second section movable relatively thereto, a split cylinder mounted between said sections, one portion of said cylinder being adapted to contact with one of said sections and another portion of said cylinder being adapted to contact with the other of said sections, yielding means surrounding said portions, means to vary said portions relatively to each other, whereby to adjust the size of the last, and means holding said sections together and permitting adjustment thereof.

10. In an adjustable last having relatively movable sections and means to hold said sections together in said relatively movable relation, means to adjust said sections relatively to each other, said means comprising a threaded bolt, a first collar loosely supported on said bolt, a second collar mounted on said bolt in threaded engagement therewith, wedge members mounted on said collars, a split cylinder, embracing said bolt, said wedge members lying between the split portions of said cylinder, and means loosely embracing said cylinder.

11. In an adjustable last having relatively movable sections and means to hold said sections together in said relatively movable relation, means to adjust said sections relatively to each other, said means comprising a threaded bolt, a first collar loosely supported on said bolt, a second collar mounted on said bolt in threaded engagement therewith, wedge members mounted on said collars, spring

means disposed between said collars, a split cylinder embracing said bolt, said wedge members lying between the split portions of said cylinder, and means loosely embracing said cylinder.

12. In an adjustable last having relatively movable sections and means to hold said sections together in said relatively movable relation, means to adjust said sections relatively to each other, said means comprising a threaded bolt, a first collar loosely supported on said bolt, a second collar mounted on said bolt in threaded engagement therewith, wedge members mounted on said collars, a split cylinder embracing said bolt, said wedge members lying between the split portions of said cylinder, said split portions being recessed to receive said wedge member, and means loosely embracing said cylinder.
